UNITED STATES PATENT OFFICE.

RALPH W. RICHARDS, OF WATERVILLE, MAINE.

POCKET SURVEYING INSTRUMENT.

1,223,615.

Specification of Letters Patent. Patented Apr. 24, 1917.

Application filed February 5, 1916. Serial No. 76,383.

To all whom it may concern:

Be it known that I, RALPH W. RICHARDS, a citizen of the United States, residing at Waterville, in the county of Kennebec and 5 State of Maine, have invented certain new and useful Improvements in Pocket Surveying Instruments, of which the following is a specification.

This invention relates to pocket surveying 10 instruments, and particularly to that type known as "pocket transits".

My improvements permit the use of the instrument as an alidade, give increased convenience of use as a marching compass, 15 and increase the field of vision when used as a level. Additional features of value are secured by special relations of the parts and will be pointed out hereinafter.

The preferred embodiment of the invention 20 is illustrated in the accompanying drawings, in which:—

Figure 1 is a plan view of the complete device opened out to show the various connected parts thereof;

25 Fig. 2 is a view of the bottom of the device, as shown in Fig. 1, except that the forward and rear sights are folded down;

Fig. 3 is a view of the device closed, and in condition for use as a marching compass. 30 In this condition it is available for use in orienting plane tables, etc.;

Fig. 4 is a side elevation showing the device arranged for use as an alidade and for analogous purposes;

35 Fig. 5 is a similar view to Fig. 4 but showing in full lines the device arranged for use as a transit, and in dotted lines the positions assumed by the parts when arranged for use as a level; and

40 Fig. 6 is an end view of the instrument closed, as in Fig. 3.

The case of the device is formed of a relatively thick case portion 11 and a relatively thin lid portion 12 both rectangular 45 in general form and hinged together by an offset hinge 13, so that the outer faces of the case and lid portions swing into a common plane when the device is opened out. The side edges of the case and lid portions 50 also are alined in this condition, and serve as ruling edges when the device is used as an alidade. To facilitate such ruling, grooves 14 are formed, as shown, along the edges of the case and lid members, to offer 55 a sharp fiducial edge. Graduations 15 are

added, different graduations being placed on the different ruling edges if desired.

The portions 11 and 12 are preferably made of aluminum or aluminum alloy to secure lightness and in this case the outer 60 faces are reinforced with bronze or gun-metal plates 16 and 17, so that the ruling or fiducial edges shall be relatively hard and durable. The hinge 13 is preferably of bronze or gun-metal as are all other 65 working parts, such as sights, etc. The case and lid portions 11 and 12 of the case are so formed as to interengage by means of lugs 18 and recesses 19 when closed, so as frictionally to retain the instrument in 70 closed condition. This also protects the instrument from injury by shocks to which it is liable when carried in the pocket, and which might otherwise destroy the alinement of its parts.

75 The case portion 11 carries in a suitable recess or chamber the usual magnetic compass. The needle of this is shown at 20, and the graduated dial ring at 21. The cover glass 22 of the compass chamber is 80 sunk below the top surface of the case portion 11 to allow clearance for the front sight to lie between the case portion 11 and lid portion 12 when these are closed together. Also mounted in the compass chamber is the usual pivoted level 23 which is 85 movable by means of a lever 24 housed in a countersink or recess 25 in the outer face of case portion 11. (See patent to Brunton No. 526,021, September 18, 1894). The 90 level 23 is provided with a vernier index 26 coacting with a graduated arc 27.

The graduated ring 21 is adjustable to correct for magnetic deviation but as such adjustment is common and is not involved 95 in the present invention the means for securing the adjustment is not shown in the drawings.

The compass needle 20 is damped by a pivoted lever 28 actuated by the depression 100 of a plunger 29 projecting above the top surface of case portion 11. This plunger 29 is depressed by the closing of the lid portion 12 as in the Brunton patent above cited. In order, however, to permit the release of 105 the needle when the lid portion is closed I cause the plunger 29 to abut against a pivoted and resilient plate 30 carried by the lid portion 12 instead of causing it to abut against the lid portion itself. This plate 30 is 110

mounted over a recess 31 into which it may be depressed by pressure with the thumbnail to release the needle temporarily. When a continued release is desired the 5 plate 30 is swung out on its pivot 32 to release the plunger 29. A bevel 33 allows it to wipe down plunger 29 when it is swung back.

The front sight consists of a slotted main 10 portion 34 hinged at 35 to the case portion 11 and having a hinged extension 36. The slot in the portion 34 is bisected longitudinally by a sight wire 37 and the extension 36 is provided with a peep sight 38 and a 15 sighting point 39 as shown. The front sight folds down on hinge 35 across the cover glass 22 and lies in recesses 40 and 41 in case portion 11. The recess 41 also accommodates the levels 42 for leveling plane tables, etc., as 20 will be obvious. A luminous point 43 is provided to coat with a luminous tip 44 on needle 20, for convenience of use in night marching.

The lid portion 12 is provided with a sight 25 slot 45 and an aperture 46 which is shown as circular, but may be of any shape desired, for example, rectangular. Countersunk into the inner side of the lid portion 12 is a glass 47 silvered over its entire back, except where it overlies slot 45 and aperture 46. A sight line 48 is engraved in the glass to form a continuation of the imaginary center line of slot 45 across the aperture or window 46. When the mirror is used the slot 45 serves 35 as a sight line.

A rear sight 49 is hinged at 50 to lid portion 12 and when out of use is housed in a recess in the outer face of the lid portion. It is provided with a sight slot 51 and a sighting 40 notch 52 as shown.

A threaded socket 53 to receive the attaching screw of a tripod is provided.

The axes of hinges 13, 35 and 50 are all perpendicular to the side ruling edges of the 45 case and lid members 11, and 12, and are all parallel to the plane of the outer faces of members 11 and 12. The sights 37, 38, 39, 45, 48, 51 and 52 all lie in a plane perpendicular to the bottom or outer face of the member 50 11 and parallel to the side ruling edges thereof in all positions of the sights. Consequently all lines of sight must lie in this plane regardless of what sights are used.

For use as an alidade the device is 55 ranged as shown in Fig. 4, sights 52 and 39 being used. In some cases where a short ruling edge will suffice the lid portion 12 may be placed substantially vertical and the sights 48, 45 and 37 used.

For use as a transit the familiar Brunton 60 method may be adopted with the device in the full line position of Fig. 5 in which the mirror is used. In this case the sights are the slot 45 and wire 37. Where a support 65 is available, so that the compass need not be

read while sighting, other arrangements of the sights may be used and will suggest themselves. It should be noted that in the full line position of Fig. 5 the offset of hinge 13 causes the window 46 to drop below the line of sight. This permits the use of a large window without encroaching on the useful area of the mirror.

For use as a level the device is positioned as shown in dotted lines in Fig. 5. This 70 brings the large window 46 into the line of sight. The device is held on edge and the eye is placed at the peep sight 38. Sights are taken on the line 48. The bubble is observed in the mirror. The large window is here of 75 the greatest utility permitting the observer to recognize distant objects with certainty.

Use as a marching compass and also for leveling and orienting tables is possible even 80 when the device is closed. As indicated in Fig. 3 the tip 44 of the needle, the north point 43 and the levels 42 are visible through 85 window 46. All that is necessary is to release the needle by proper actuation of the catch plate 30.

The offset hinge and the special relation 90 existing between this and the window are important. The hinge permits the use of a thick casing with a thin lid, where alinement of their edges is necessary when the lid is 95 opened back. The offset hinge with the window set close to the hinge causes the window to drop below the line of sight when the device is used as a reflecting transit. It thus becomes possible to use a much larger window 100 than can be had in prior structures, a feature of great value in all uses of the instrument in which the line of sight is through the window. Examples of such use are when the instrument is used as a 105 level, and as a direct view transit.

Having thus described my invention, what I claim is:—

1. A pocket surveying instrument comprising in combination, a casing having a 110 straight ruling edge; a magnetic compass inclosed by said casing; a lid having a straight ruling edge, a reflecting inner surface, and a sight line on said surface; a hinge connecting said casing and lid for causing their ruling edges to be in alinement to produce a continuous ruling edge when the lid is swung back; and folding 115 sights one carried by the lid and another by the casing.

2. A pocket surveying instrument comprising in combination a casing having opposed parallel ruling edges; a magnetic compass inclosed by said casing; a lid having opposed parallel ruling edges, a sight 125 slot and a reflecting inner surface; a hinge connecting said casing and lid for causing their ruling edges to be in alinement to produce continuous parallel ruling edges when the lid is swung back; and folding sights 130

- one carried by the lid and another by the casing.
3. A pocket surveying instrument comprising in combination, a casing having a straight ruling edge; a magnetic compass inclosed thereby; a lid provided with a sight slot and a reflecting inner surface; a hinge connecting said casing and lid; and a folding sight carried by said casing.
- 10 4. A pocket surveying instrument comprising in combination, a substantially rectangular casing having a side grooved to present a sharp ruling edge; a substantially rectangular lid having a side grooved to 15 present a sharp ruling edge; a hinge connecting said lid and casing and for causing the ruling edges thereof to be in alinement when the lid is opened out; and folding sights one carried by the lid and the other 20 by the casing.
5. In a combined transit and level of the reflecting pocket type, the combination of a casing; a magnetic compass and a leveling device mounted in said casing; a folding 25 sight carried by said casing; a lid for said casing, provided with a reflecting inner surface, a window and a sight line; and a hinge connecting said casing and lid said hinge being offset, for causing the window to be in 30 the line of sight when the lid is adjusted for use of the device as a level, and out of the line of sight when the lid is adjusted for use of the device as a reflecting transit.
6. In a combined transit and level of the reflecting pocket type, the combination of a casing; a magnetic compass and a leveling device mounted in said casing; a folding 35 sight carried by said casing; a lid for said casing provided with a reflecting inner surface, a window and a sight line; an offset hinge connecting said casing and lid, said hinge and window being so arranged that 40 said window is in the line of sight in the leveling adjustment of the device, out of the line of sight in the reflecting transit adjustment of the instrument, and permits a view 45 of the magnetic compass in the closed position of the instrument; means operable by
- the closing of the lid for damping the needle of the magnetic compass; and means for releasing said damping means while the lid is closed.
7. A combined transit, alidade and level of the pocket type comprising in combination a casing having a straight ruling edge; 50 a magnetic compass and a leveling device mounted in said casing; a lid having a straight ruling edge, a window, a reflecting inner surface, and a sight line extending across said reflecting surface and window; 55 a hinge connecting said lid and casing said hinge being offset to bring said ruling edges into alinement when the lid is swung back, and said window being located between said reflecting surface and hinge; and folding 60 sights one carried by said casing and another by said lid.
8. The combination with a pocket surveying instrument including a magnetic compass, folding sight and hinged reflecting 65 lid provided with a window permitting a view of the compass in the closed position of said lid, of a damper for the compass needle normally held in damping position by the lid when closed; and means for releasing said damper while the lid is closed.
9. In a combined transit and level of the reflecting pocket type, the combination of a casing; a magnetic compass and a leveling device mounted in said casing; a folding 70 sight carried by said casing; a lid for said casing provided with a reflecting inner surface, a window and a sight line; an offset hinge connecting said casing and lid, said hinge and window being so arranged that 75 said window is in the line of sight in the leveling adjustment of the device, out of the line of sight in the reflecting transit adjustment of the instrument, and permits a view of the magnetic compass in the closed position of the instrument; and means for damping and releasing the needle of the magnetic compass while said lid is closed.

In testimony whereof I have signed my name to this specification.

RALPH W. RICHARDS.
